UNITED STATES PATENT OFFICE.

FRANK A. FALK, OF STACYVILLE, IOWA.

WAGON-BOX CONSTRUCTION.

No. 920,299.

Specification of Letters Patent.

Patented May 4, 1909.

Application filed December 17, 1907, Serial No. 406,846. Renewed February 5, 1909. Serial No. 476,313.

To all whom it may concern:

Be it known that I, FRANK A. FALK, a citizen of the United States, residing at Stacyville, in the county of Mitchell and State of Iowa, have invented certain new and useful Improvements in Wagon-Box Construction, of which the following is a specification, reference being had to the accompanying drawings.

10 My invention relates to improvements in the construction of wagon-boxes and particularly to improvements in the side-boards which are used in such structures; and an object of my invention is to provide such side-boards with means to enable them to be readily put in place and to be removed therefrom.

Another object of my invention is to provide side-boards of the character described 20 which may be built to a great height in order to accommodate a large load and which are interchangeable as regards position.

A third object of my invention is to provide side-boards in which one of the end 25 cleats heretofore used to hold the end board may be dispensed with.

A further object of my invention is to provide a side-board which will retain the material even when the opposed edges of two 30 side-boards are separated by a slight interval.

In the drawings illustrating the principle of my invention and the best mode now known to me of applying that principle, Figure 1 is an elevation of so much of a side 35 of a wagon box as is necessary to illustrate my invention, the inside of the box being shown; Fig. 2 is a detail showing the manner in which two side-boards fit together; Fig. 3 is a detail showing the end board in section 40 and the side-boards slightly separated from each other; Fig. 4 is a detail in perspective of an end of one of the side-boards; Fig. 5 is a plan of an end of a side-board, the end board being shown in place; and Fig. 6 is an end 45 view of one of the side-boards.

Each of the side-boards *a* is provided on each side with a pair of cleats *b*. The sides *c*, *d* of these cleats are parallel to each other and are perpendicular to the edge of the 50 board, while the ends *e*, *f* are inclined to the edge of the board. Further, the upper ends *e* of the cleats at opposite ends of the same side-board converge downwardly; and the same is true of the lower ends *f*. The lower 55 end *f* of the cleat is shaped to fit snugly upon the upper end *e* of the next lower cleat. The

lower edge of each side-board is provided with a strap *g* which, when the side-boards are placed in position, overlaps the upper edge of the side-board next below upon its 60 inner face. Each side-board is provided on its inner face with an end cleat *h* the inner side or edge *k* of which is parallel to the side *c* of the cleat *b* whereby a slot *i* is left for the insertion of the end *j*. By reason of the fact 65 that the cleats *b* are continuous, when the side-boards are placed in position, and that the sides *c* are parallel to the inner edge *k* of the cleat *h*, the side-boards may be separated by an interval, as is shown in Fig. 3, without 70 a crack being left between the cleat ends for the leakage of the material held in the wagon box. In the old construction, an additional cleat was necessary for the holding of the end board; and where the side-boards were separated 75 by a slight interval, a crack was left between the opposed ends of the cleat, whereby leakage of the material held in the wagon box resulted. The side-boards *a* are identical in construction which makes their manufacture 80 cheaper as they can be made in large quantities and in standard sizes.

As is clearly indicated in Figs. 1 and 2 the end *f* of each cleat slides in between the upper ends *e* of the cleat of the board next below. 85 This arrangement of the cleats *b* serves to obviate the inconvenience which results from the arrangement of the cleats heretofore used. In the latter arrangement some of these cleats had to be placed back a little and 90 others forward a little so as not to interfere with each other; and unless specially built, the box could not be provided with an extra board without the removal and replacement of the cleats. With the arrangement herein 95 disclosed, it is not necessary to have a particular side-board *a* come in a particular order in the building of a high box, as the side boards will fit together in any order. Further, the wagon-box can be built to any 100 height out of boards from stock, as they are all alike. This is of great advantage where large loads are hauled. Another advantage resulting from my new construction lies in the ease with which the wagon-box may be 105 dismantled or taken apart. After one of the side-boards is started, there will be no binding of the cleats, the inclination of the upper and lower ends of the cleats being such as to permit one end of the side-board to be lifted 110 out entirely without binding. In the ordinary construction heretofore pursued, if one

end is lifted alone or faster than the other end, the cleats bind. In assembling the side-boards *a*, no difficulty is experienced in putting down the board, as the convergence 5 of the end faces of the cleats tends to guide the upper board into place.

I claim:

1. In a structure of the class described, a side-board provided with cleats a part of 10 each of which projects beyond a longitudinal edge of the side-board; the end face of the projecting part of each cleat being inclined to the longitudinal edge of the side-board and the opposite end face of each cleat being inclined 15 to the longitudinal edge of the side-board; said inclined end faces having the same general inclination.

2. In a structure of the class described, a side-board provided with an end cleat and 20 with a second cleat having one side parallel to the opposed side of the first-named cleat; the ends of the last-named cleat being inclined to the longitudinal edge of the side-board; said cleats being separated by a slot. 25

3. A series of side-boards each side-board

being provided with a pair of cleats the upper and lower ends of which are inclined to the longitudinal edge of the side-board and converge downwardly; the lower ends of the cleats on each side-board lying within the upper ends of the cleats on the side-board next below. 30

4. The combination with an end board, of a series of side-boards; each of the latter being provided with a pair of cleats the ends of 35 which are inclined to the longitudinal edge of the side-board and with an end cleat the inner side of which is parallel to the opposed side of the nearest of said pair of cleats; said end board being held between said end cleat 40 and the nearest cleat of said pair.

In witness whereof I have hereunto set my hand in the presence of the two undersigned witnesses at said Stacyville this 10th day of December, A. D. 1907.

FRANK A. FALK.
